WRENCH HAVING CAM LEVER FOR SWINGING AND LOCKING A PIVOTED OUTER JAW

Edwin A. Schumacher, Wichita, Kans., assignor of one-half to Theodore R. Breed, Wichita, Kans.

Application December 8, 1948, Serial No. 64,172

1 Claim. (Cl. 81—78)

1 The present invention relates to new and useful improvements in wrenches of the sliding jaw type and more particularly to a pivoted outer jaw for the wrench and means for tightening and locking the gripping action of the outer jaw following an approximate adjustment of the sliding jaw.

An important object of the invention is to provide a pivoted outer jaw for the wrench with lever working against inclined cam surfaces for tightening and locking the outer jaw to improve the gripping action of the wrench.

A still further object is to provide a tool of this character of simple and practical construction, which is strong and durable, efficient and reliable in operation and relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the outer jaw in locked position.

Figure 2 is a similar view showing the outer jaw in a released position.

Figure 3 is a fragmentary side elevational view with parts broken away and shown in section to show the closing and locking faces for the pivoted outer jaw and

Figure 4 is a rear elevational view.

Referring now to the drawing in detail wherein for the purpose of illustration I have disclosed a preferred embodiment of the invention, the numeral 5 designates a shank of the wrench having a handle at one end and having its opposite end substantially rectangular in cross section and formed with threads 6 on its opposite longitudinal surfaces for engagement by a nut 7 carried in an opening 8 of a traveler 9 which is formed with an offset 10 to provide a sliding jaw for the wrench.

The outer end of shank 5 is bifurcated as shown at 11 and is provided with a transverse pin 12 on which an outer jaw 13 is pivoted, the jaws 10 and 13 having coacting toothed jaw faces 14 and 15 respectively.

The base of the bifurcated outer end portion 11 is indicated at 16 and is formed with a forwardly inclined face 17 with a coil spring 18 positioned between the inclined face 17 and the inner edge of the pivoted jaw 13. The ends of the spring 18 are anchored on retaining pins 19

and the spring 18 is positioned forwardly of the pivot pin 12 whereby to exert its pressure on the pivoted jaw in a direction to open the latter.

The rear edge of shank 5 at the base portion 16 for the bifurcated outer end 11 is formed with a rearwardly projecting shoulder 20 having a forwardly inclined rear surface 21 which is accentuated at the top of the shoulder to provide a rearwardly inclined upper surface 22.

A lever 23 is formed with a bifurcated outer end 24 which receives the rear end portion of pivoted jaw 13 and is pivoted thereto by a transverse pin 25.

A lug 26 projects laterally from the inner edge 15 of lever 23 adjacent its bifurcated outer end 24 and is formed with a slightly rounded outer edge 27 to function as a cam for riding on the inclined surface 21 and inclined surface 22 of the shoulder 20.

In the operation of the tool, the work such as a pipe or the like 28 is placed between jaws 10 and 13 and the nut 7 adjusted to move the traveler 9 and jaw 10 into an approximate adjustment with respect to pivoted jaw 13. During this action, the lever 23 is swung outwardly into the position as shown in Figure 2 of the drawing and an inward movement of the lever will cause the cam 27 to ride on the inclined surface 21 of shoulder 20 to cause the rear end of jaw 13 to move outwardly and cause the front end of jaw 13 to move inwardly into tight gripping engagement with the work. When the cam 27 rides onto the inclined upper surface 22 of the shoulder 20 the jaw 13 will be locked against releasing movement.

The work is released by swinging the lever 23 rearwardly.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A wrench comprising a shank having a sliding jaw and a pivoted outer jaw coacting with the sliding jaw, spring means opening the outer jaw, a lever pivoted at the rear end of the outer

jaw, and camming means between the lever and the shank to exert a closing pressure on the outer jaw, said camming means comprising a rounded lug on the lever, and a shoulder extending from the rear side of the shank and having an inclined rear surface and an inclined upper surface, said lug riding on the rear surface to exert a closing pressure on the outer jaw and said lug riding on the upper surface to lock the outer jaw in a closed position.

EDWIN A. SCHUMACHER.
